UNITED STATES PATENT OFFICE.

MINNIE M. DENDINGER, OF LOUISVILLE, KENTUCKY.

ELEVATOR.

1,248,279.

Specification of Letters Patent.

Patented Nov. 27, 1917.

Application filed April 16, 1915. Serial No. 21,705.

To all whom it may concern:

Be it known that I, MINNIE M. DENDINGER, a citizen of the United States residing at Louisville, in the county of Jefferson and State of Kentucky, have invented a new and useful Elevator, of which the following is a specification.

This invention has reference to elevators, and particularly to passenger elevators, and 10 its object is to provide for the segregation of passengers desiring to go to different floors. In accordance with the present invention the elevator is provided with partitions dividing its interior into an appropriate 15 number of compartments, which extend to the front of the elevator, and the doors at the different floors protecting the elevator shaft from access and permitting access to the elevator itself are of such width or extent of travel as to give admission simultaneously to all of the compartments.

Since it may be desirable at times to use only certain ones of the compartments or to enlarge a compartment by coalescing two 25 or more of such compartments into one, the partitions are so made and mounted that they may be moved entirely out of the way without removing them from the elevator car.

30 The invention will be best understood from a consideration of the following detailed description taken in connection with the accompanying drawings forming a part of this specification, with the understanding, 35 however, that while the drawings show a practical embodiment of the invention, the latter is not confined to any strict conformity with such showing, but may be changed and modified so long as such changes and modifications mark no material departure from 40 the salient features of the invention.

In the drawings:

Figure 1 is a perspective view of the elevator car as seen from the front.

45 Fig. 2 is a front-to-rear vertical section of the elevator car taken at about the mid point of the width of the car.

Fig. 3 is a front elevation of the car and one type of door structure which may be 50 employed.

Referring to the drawings, there is shown an elevator car 1, which so far as its general structure is concerned may follow the usual lines, except that the car may be made wider 55 than customary to permit division of its in-

terior into a suitable number of compartments to correspond to the number of floors to which the elevator travels.

Secured within the car body at the rear portion thereof and near the top and bottom of the car body are beams 2, 3, respectively, these beams being preferably of angle metal, each with one flange arranged horizontally and directed toward the front of the car.

60 The beam or bar 2 is located as near the bottom of the car as is convenient or desirable, and the beam or bar 3 is for reasons which will presently appear spaced a short distance from the top of the car.

65 Each beam or bar 2 and 3 has perforations 4 and 5, respectively in suitable spaced relation and adapted to the perforations 4 and 5 are pintles 6 and 7 at respective ends of the rear end member 8 of a partition 9 70 made up of pivotally united strips 10 connected together in lazy-tong order to provide for expansion and collapse of the partition. No attempt is made to show the 75 details of the construction of the collapsible 80 and extensible partitions since any one of many well known constructions for this purpose may be used.

At the front edge of the partition is a front 85 upright bar or member 11, as is customary in partitions of the general character illustrated. At the top and bottom ends of the front bar 11 are bolts 12, 13, respectively, 90 adapted to engage in passages 14, 15 respectively in the bottom and top of the elevator car near the front thereof. The perforations 4 and 5, and the perforations or 95 passages 14 and 15 are correspondingly spaced with relation to the width of the car, so that with the pintles 6 and 7 engaging in the perforations 4 and 5 and the sliding members of the bolts 12 and 13 engaged in the perforations 14 and 15, the interior of the car is divided by the partitions 9 into a suitable number of compartments. In the 100 drawing four such compartments are shown, being defined by three partitions. On the upper portion of the car, or in other appropriate position with respect to the car are suitable legends indicated at 16 to individualize the compartments to separate floors to which the elevator travels. For instance, one compartment may be reserved for the first floor to which the elevator travels, the next compartment may be reserved for the 105 110

second floor, and so on, the legends indicating the particular floors for which the compartments are reserved.

The partitions 9 are made so that when in the expanded position, they reach from the rear to the front of the car, but these partitions may be collapsed so as to be shorter than when extended, and then may be moved about the axis of the pintles 6 and 7 so as to lie flat against the back wall of the car, with the front member 11 between the horizontal webs of the bars 2 and 3, as illustrated in Fig. 1.

In order to insert and remove the partitions, the rear upright 8 is shorter than the distance between the horizontal webs of the bars 2 and 3 by a distance or amount somewhat greater than the length of the pindle 6, wherefore the pindle 7, which is longer than the pindle 6, may be introduced through the perforation 5, and the partition be lifted sufficiently to permit the insertion of the pindle 6 in the perforation 4, and when the end member is lowered to rest upon the bar 2, the pindle 7 is still within the perforation 5. When the partition is extended toward the front of the car, and the bolts 12 and 13 are moved to engage in the perforations 14 and 15, the partition is held in the extended position to form a division wall between the car. The bolts 12 and 13 may be of any appropriate type whereby they become locked in the projected position. On each floor the elevator shaft is provided with a closure which in the particular showing of the drawing is represented by doors 17, one or more of which may be employed, and in the particular showing two such doors are illustrated in Fig. 3 to facilitate the closure of so wide a door opening as some forms of cars equipped with the present invention would demand.

The doors 17 may be of the expandable and contractible type similar to the partitions 9, and since such doors are in common use, it is unnecessary to describe them in detail. The doors 17 are to be taken as typical of any appropriate closure for the elevator openings.

When passengers desire to go to some particular floor, they enter the compartment, whereupon the elevator operator will know that such passengers desire to reach a certain floor without the necessity of announcement on the part of the passenger as to the floor desired. The elevator conductor may be stationed in any one of the compartments, but will usually be located in the compartment designated "1st Floor." Because of the open character of the partitions, the elevator conductor can readily see across

the full width of the elevator car, and may ascertain for just what floors the elevator contains passengers, and therefore if there be no passengers in one or more of the compartments, it is unnecessary to stop at said floor unless it be that some passenger desires to enter.

It will be understood, of course, that the legends 16 need not be confined to the elevator car, but may be placed elsewhere, the purpose being to guide passengers to the proper compartments.

While the elevator has been illustrated in the drawings as provided with three partitions, and the perforations for the attachment of the apparatus to the car are of similar number to the partitions, it will be understood that the perforations 4 and 5 in the bars 2 and 3 and the perforations 14 and 15 may be of a greater number than shown, or be otherwise arranged so that the partitions may be equispaced or be irregularly spaced, as may be desired.

What is claimed is:

1. An elevator car provided with bars near the top and bottom at the rear, said bars having matching perforations therein, and the car also being provided with like perforations near the front, and expandable and collapsible partitions provided with front and rear uprights with the rear uprights having pintles adapted to the perforations in the top and bottom, the rear bars and the front uprights being provided with fastening means adapted to the perforations at the front portion of the elevator car.

2. An elevator car provided with bars near the top and bottom at the rear, said bars having matching perforations therein, and the car also being provided with like perforations near the front, and expandable and collapsible partitions provided with front and rear uprights with the rear uprights having pintles adapted to the perforations in the top and bottom, the rear bars and the front uprights being provided with fastening means adapted to the perforations at the front portion of the elevator car, the length of the rear uprights of the partitions and the spacing of the bars at the rear of the car being related to permit the attachment to, and removal of, the rear uprights of the partitions from the perforations in the rear bars of the car.

In testimony, that I claim the foregoing as my own I have hereto affixed my signature in the presence of two witnesses.

MINNIE M. DENDINGER.
